United States Patent Office

Des. 218,170
Patented July 28, 1970

218,170

FACSIMILE TRANSCEIVER

Karl E. Kober, Rush, N.Y., assignor to Xerox Corporation, Rochester, N.Y., a corporation of New York

Filed Dec. 26, 1968, Ser. No. 15,121

Term of patent 14 years

Int. Cl. D14—01

U.S. Cl. D26—14

FIG. 2

FIG. 6

F/G. 3

FIG. 4

FIG. 5

FIG. 1 is a perspective view of a facsimile transceiver showing my new design;

FIG. 2 is a front elevational view thereof;

FIG. 3 is a top plan view thereof;

FIG. 4 is an elevational view taken from one side thereof;

FIG. 5 is an elevational view taken from the side opposite that shown in FIG. 4;

FIG. 6 is a rear elevational view thereof; and

FIG. 7 is another perspective view thereof.

The broken line representation of a telephone handset in FIG. 1 is for purposes of illustration only.

I claim:

The ornamental design for a facsimile transceiver, as shown and described.
